UNITED STATES PATENT OFFICE

96,817

DESIGN FOR A COMBINED TRACTOR AND REFRIGERATOR TRUCK TRAILER

Isaac J. Clark, Washington, D. C.

Application November 10, 1934, Serial No. 53,963

Term of patent 7 years

To all whom it may concern:

Be it known that I, Isaac J. Clark, a citizen of the United States, residing in Washington, in the District of Columbia, have invented a new, original, and ornamental Design for a Combined Tractor and Refrigerator Truck Trailer, of which the following is a specification, reference being had to the accompanying drawings, forming a part thereof.

Figure 1 is an elevational view of the combined tractor and refrigerator truck trailer, showing my new design,

Figure 2 is a plan view of the same, and
Figure 3 is a perspective view of the same.

The dominating features of my design are shown in solid lines and include the provision of an extraordinarily large cab having a pair of windows on each side and a flat, elongated forwardly sloping roof and a trailer provided with a pair of refrigerator type doors on one side and having a rounded cornerless roof with a forwardly projecting visorlike front portion.

I claim:

The ornamental design for a combined tractor and refrigerator truck trailer, as shown and described.

ISAAC J. CLARK.
